JOHN H. VOGT, OF READING, AND HARRY MCADAMS, OF PHILADELPHIA, PENNSYLVANIA, ASSIGNORS TO THE NOLDE AND HORST COMPANY, OF READING, PENNSYLVANIA, A CORPORATION OF PENNSYLVANIA

STOCKING AND PROCESS OF MAKING

Application filed October 27, 1930. Serial No. 491,421.

This invention relates generally to circularly knit goods as stockings or the like, and more particularly to those formed with one or more elastic belts or garter bands adapted to securely retain them in place, when in use, without other support.

And the present improvements comprise a knit tubular article having one or more supporting band portions each consisting of an annular pocket enclosing an encirclingly wound elastic thread, parts only of the latter being secured to said pocket to effect a tensioned resistance to an enlarging circular stretch.

A preferred embodiment of the improvements, their inherent advantages, neat appearance, and simple and economical formation during the usual knitting operation, will be more fully described in connection with the accompanying drawings, and the novel features thereof set forth in the appended claims.

Fig. 1 indicates a stocking having a ribbed top and embodying the improvements, an outer-wall portion of one pocket being broken away to show the enclosed windings of the elastic thread.

Fig. 2 is an enlarged diagrammatic longitudinal section through a pocket portion of the stocking on the line 2—2 of Fig. 1.

Fig. 3 is an enlarged diagrammatic transverse section through said pocket, on the line 3—3 of Fig. 1.

Fig. 4 is a diagrammatic view showing the elastic thread feeding finger and its relation to the needles of a knitting machine.

The drawings indicate a well known stocking or half hose consisting as usual of a top portion 5, leg portion 6 and foot portion 7.

The top portion 5, adapted to snugly fit the leg of a wearer, is preferably made, as shown, of rib-knitted fabric for greater freedom to expand, but such ribbed fabric alone does not reliably insure proper support of the stocking.

To insure such proper support, the improvements provide for the addition to said top of one or more integral garter band portions 10, each comprising free windings of

a rubber or other elastic thread 11 encircling said top 5 within a pocket 12 formed in the latter. The number of windings will determine the desired resilience, and the securing of portions of said thread to the pocket 55 wall will prevent said thread 11 from creeping in said pocket 12 and insure its proper tensioned resistance to an enlarging circular stretch.

The pocket 12 encloses and retains in hidden position the windings of thread 11; and adequate anchoring of said thread to said wall pocket may be simply secured, as shown in the preferred construction of the drawings, by interknit portions of said thread 11, 60 adjacent each end of the length forming such windings, engaging for a few wales 14 with the fabric forming a wall of said pocket 12, the intermediate portion of said wound length being free from any attachment to, though 70 confined in said pocket.

A stocking thus provided with the improved garter band portion 10 will be self supporting on the leg of a wearer. And the use of such elastic thread 11 in place 75 of a circular band, or adequate single strand, facilitates its introduction to the closed pocket 12, and allows for desired variation of garter resilience in accordance with the number of windings. And moreover such 80 windings are securely retained in proper position on said top portion 5, and are neatly hidden in the encasing pocket walls, thus forming an integral stocking garter band portion 10 of improved construction, determined elasticity, and pleasing inconspicuous 85 appearance. One or a plurality of such garter band portions 10 may be employed as desired, the drawings showing two bands arranged to spacingly divide the contracting 90 pressure on the wearer's leg.

The improved garter band portions 10 above freely set forth, may be simply and economically formed during the usual knitting operation to produce the stocking, and 95 a preferred method for this purpose will now be described.

The ribbed top portion 5 of the drawings is commonly economically knit as a continuous tube provided at spaced intervals with 100

- annular bands of varied stitch formation defining lines for severing it into individual tops having a selvage-edge at one end thereof and the other end adapted to be transferred 5 to the needles of a machine on which the leg portion 6 and foot portion 7 are knit in well known manner, completion of the stocking being accomplished by a subsequent seaming of the toe pocket as heretofore.
- 10 One common form of such special stitch defining band, known as a "French welt", produces an integral annular pocket by separation for a selected number of courses of the stitches formed on the cylinder needles from 15 those formed on the dial needles so as to produce two separate fabrics in such courses only, said stitches being interengaged above and below said special courses to knit a usual ribbed top, all as well known and understood.

For the purposes of the present improvements we provide the top 5 with one or more such usual annular pockets 12 heretofore referred to, spaced as desired lengthwise of 25 said top, and during the knitting formation thereof introduced into said pockets the encircling windings of the elastic thread 11.

In Fig. 4 we have indicated the cylinder needles 15 and dial needles 16 of a known 30 rib-knitting machine, and 17 one of a plurality of usual thread guide fingers adapted to supply thread to said needles. When the knitting operation has reached a point where 35 a pocket is desired, the needles 15 start to form a separate fabric producing one wall 20 of said pocket 12, and the needles 16 simultaneously produce the other wall 21 thereof. During such separate wall formation, we lower 40 into feeding position, indicated by full lines, a guide finger 17 carrying the elastic thread 11, which is then supplied to and interknit with the needles 15 as shown, such interknitting being preferably interrupted, after a few wales 14 sufficient to safely anchor said 45 introduced end of thread 11, by a partial lifting of said guide finger 17 to dotted position 17^a where the thread 11 will not interknit, but will be loosely laid between the separately forming fabric walls 20 and 21. The 50 guide will remain in such position only long enough to supply a determined number of encircling windings with such forming pocket, when it will be again lowered to needle feeding position for a few wales 14^a to 55 anchor it again in a later formed course on said needles 15. After such anchoring, guide finger 17 is raised to idle dotted position 17^b, withdrawing said thread from the fabric, and at this point any known cutting 60 device, as blades 22, will act to sever such withdrawn thread. The pocket 10 is then closed as usual and secures and encases the encircling wound thread, and each end of 65 the latter is securely anchored to a wall of said pocket so as to form a resilient circular

band lying wholly within and hidden in pocket 12. This operation may be repeated at intervals depending on the number of garter bands 10 that are required. Also the anchoring interknitting may be introduced at 70 other parts than the ends as described.

While we have shown and described a preferred stocking structure having a rib-knitted top portion, any stocking provided with an annular pocket portion to receive 75 the elastic thread 11 would be equally applicable. And while shown and described as a garter band, it may be equally applicable as a supporting belt or the like for other tubular knit articles.

From the foregoing description it is believed the nature of the improvements and one method of their production will be readily understood, and we do not desire to limit ourselves to such specific structure, but:

What we claim is:

1. A tubular knit stocking or the like having a top formed with an integral annular pocket, and a supporting garter formed in 90 said pocket by encircling windings of an elastic thread, limited portions only of which are secured to a wall of said pocket.

2. A tubular knit stocking or the like having a top formed with an integral annular pocket, and a supporting garter formed in 95 said pocket by encircling windings of an elastic thread, limited portions only of which are secured to a wall of said pocket by interknit engagement therewith in different courses for a plurality of wales.

3. A tubular knit stocking or the like having a top formed with an integral annular pocket, and a supporting garter formed in 100 said pocket by a plurality of encircling windings of a length of elastic thread, end portions only of said length being secured to a wall of said pocket.

4. A tubular knit stocking or the like having a top formed with an integral annular pocket, and a supporting garter formed in 105 said pocket by a plurality of encircling windings of a length of elastic thread, end portions only of said length being secured to a wall of said pocket by interknit engagement therewith in different courses for a plurality 110 of wales.

5. The process of manufacturing a tubular knit stocking or the like with an elastic supporting garter portion, which comprises 115 knitting a tubular fabric having an integral annular pocket, and during the knitting of said pocket introducing thereto an added elastic thread encircling wound within said pocket for a plurality of convolutions, and portions only of different convolutions interknit with a wall of said pocket to anchor said thread and form an elastic circular supporting band.

6. The process of manufacturing a tubular knit stocking or the like with an elastic sup-

porting garter portion, which comprises knitting a stocking top with an integral annular pocket, during the formation of the latter introducing thereto an added elastic 5 thread, interknitting an end portion of the latter for a plurality of wales with one course of said pocket wall, laying said thread in said pocket beyond said interknitting for a plurality of encircling windings, interknitting a 10 second portion of said thread for a plurality of wales in another course of said pocket wall, severing said elastic thread beyond said last mentioned interknitting and withdrawing it out of action, completing said pocket, 15 and adding a leg and foot portion to said top.

In testimony whereof we affix our signatures.

JOHN H. VOGT.
